UNITED STATES PATENT OFFICE.

JOHN P. O'BRIEN, OF CASTLE ROCK, COLORADO, ASSIGNOR OF ONE-
FOURTH TO GEORGE COLE BRISCOE, OF CASTLE ROCK, COLORADO.

MEANS FOR FASTENING HORSESHOES.

No. 843,907.

Specification of Letters Patent.

Patented Feb. 12, 1907.

Application filed June 20, 1906. Serial No. 322,623.

To all whom it may concern:

Be it known that I, JOHN P. O'BRIEN, a citizen of the United States, residing at Castle Rock, in the county of Douglas and State 5 of Colorado, have invented certain new and useful Improvements in Means for Fastening Horseshoes; and I do declare the following to be a full, clear, and exact description of the invention, such as will enable others skilled 10 in the art to which it appertains to make and use the same, reference being had to the accompanying drawings, and to the letters and figures of reference marked thereon, which form a part of this specification.

15 My invention relates to improvements in means for fastening shoes to the hoofs of horses, my object being to provide a device whereby the shoe is readily detachable for the purpose of resting the feet of the horse 20 during the night, for instance.

25 In my improved construction nails of special form are driven into the hoof of the horse and clenched in the usual way. The lower extremities or heads of these nails are enlarged and tapped to form threaded recesses 30 adapted to receive screws passed through the horseshoe and engaging the threaded recesses of the nails. In removing the shoe it is only necessary to take a screw-driver and take out the fastening-screws. The nails of course remain in place. The reattaching of the shoe is equally easy and can be performed by any one.

35 Having briefly outlined my improved construction, I will proceed to describe the same somewhat more in detail, reference being made to the accompanying drawings, in which is illustrated an embodiment thereof.

40 In the drawings, Figure 1 is an underneath view of the hoof of a horse, showing a shoe applied in accordance with my invention. Fig. 45 2 is a side elevation of the same, partly in section. In this case the shoe is shown in its natural position when the foot of the horse 45 engages the ground or other surface beneath him. Fig. 3 is a detail view of my improved fastening means, showing the nail and its co-operating screw. In this view the two members are detached. Fig. 4 is a view taken at 50 right angles to Fig. 3, showing a screw inserted in the threaded recess of the nail. Fig. 5 is a sectional view illustrating another form of construction.

55 The same reference characters indicate the same parts in all the views.

Let the numeral 5 designate a horseshoe, which may be of any ordinary construction, the only difference being that the holes at their outer extremities are enlarged to receive screw-heads, whereby the latter may be countersunk when the shoe is applied to the hoof of the animal.

60 My improved fastening means consists of a nail member 6 and a screw member 7. The nail member 6 is provided with a head 6^a, 65 which in this case is shown cylindrical in form, though this particular form is not absolutely essential. In this head portion is formed a threaded recess adapted to receive the screw 7. The part 6 of the nail member is formed 70 thin and tapering from the shoulder 6^c of the head to the point.

75 It must be understood that the special form illustrated in the drawings is not essential, since the nail, so far as its general construction is concerned, may be made in many different shapes, the only indispensable feature being that it shall be provided with a head member having a threaded recess to receive the fastening-screw. It is evident that 80 the reverse of this construction might be employed—that is to say, the screw might have the interiorly-threaded recess and the nail might have the threaded shank, as shown in Fig. 5, though the form illustrated in the 85 principal views is believed preferable, since if the nail were provided with a threaded shank the thread of this shank would possibly be upset or injured by the blows of the hammer in driving the nail into the hoof. It 90 is evident, however, that the scope of the invention is sufficient to include both of these forms of construction.

95 In Fig. 5 let the reference character 6^b represent the threaded shank of the nail, while the reference character 8 designates the hollow screw or the screw provided with the interiorly-threaded recess adapted to co-operate with the threaded shank to form the shoe-fastening means.

100 In applying the shoe by the use of my improved fastening means the hoof is first shaped or trimmed and the shoe formed to fit the hoof. The shoe is then applied to the hoof and a pointer inserted through each 105 nail-hole, forming marks for the nails. By the use of a small auger or bit holes are formed in the hoof to receive the heads 6^a of the nails. The nails are then driven into the hoof until the heads 6^a are embedded in the 110

recesses formed, the outer extremities of the said heads being flush with the bottom of the hoof. The shoe is then put in position and the screws passed through the shoe and inserted in the threaded recesses of the nails. The points of the nails are then bent down or clenched on the outside of the hoof, whereby the fastening devices are secured tightly in place.

10. In securing the shoe by the means shown in Fig. 5 the same steps would be followed. In this case it would of course be necessary for the holes in the shoe to be formed somewhat larger in order to receive the enlarged hollow shank of the screw.

Having thus described my invention, what I claim is—

1. Means for fastening horseshoes, comprising two detachable members, one consisting of a nail adapted to be applied directly to the hoof of the animal, while the other consists of a screw adapted to pass

through the shoe and connect in operative relation with the nail member.

2. Means for fastening horseshoes, comprising a hoof member consisting of a nail, and a shoe member consisting of a screw, one of the members being provided with a threaded recess and the other member with a threaded shank adapted to enter the said recess.

3. Means for fastening horseshoes, comprising a hoof member consisting of a nail, having a head provided with a threaded recess, and a shoe member comprising a screw having a shank adapted to enter the threaded recess of the hoof member.

In testimony whereof I affix my signature in presence of two witnesses.

JOHN P. O'BRIEN.
